UNITED STATES PATENT OFFICE.

WHITFIELD J. HAINER, OF PROVIDENCE, RHODE ISLAND, ASSIGNOR TO HAINER
BOOKKEEPING MACHINE COMPANY, OF PROVIDENCE, RHODE ISLAND, A CORPO-
RATION OF RHODE ISLAND.

AUTOGRAPHIC REGISTER.

1,143,386.

Specification of Letters Patent. Patented June 15, 1915.

Application filed March 23, 1912. Serial No. 685,878.

To all whom it may concern:

Be it known that I, WHITFIELD J. HAINER, a subject of the King of England, residing at the city of Providence, in the county of Providence and State of Rhode Island, United States of America, have invented certain new and useful Improvements in Autographic Registers, of which the following is a specification.

10 This invention relates to autographic registers and has for its object to provide a small or pocket-size of this type of register, the same comprising a body portion constituting a magazine in which a plurality of 15 continuous strips of sales slips are stored in accordion-like folds, the same having a writing plate above it, over which the strips are passed, and a cover operatively connected to the writing plate so that when 20 said cover is moved from its closed to its open position the plate will be raised to release the strips in the magazine which may then be readily drawn therefrom. The connection to this cover is also made so that in 25 moving the cover back to its closed position said plate is lowered to bind the contents of the magazine in position.

A further object of the invention is to 30 arrange the mechanism so that when opened the cover will form a suitable receptacle for the sales slips after they have been used or passed over the writing plate.

A further object of the invention is to 35 provide metal hinges for the carbon sheets and means for retaining said sheets by the hinges so that they will lie in line with the travel of the continuous sales slips.

With these and other objects in view, the 40 invention consists of certain novel features of construction, as will be more fully described and particularly pointed out in the appended claims.

Of the accompanying drawings: Figure 1— is a perspective view illustrating my 45 improved pocket register in closed position. Fig. 2— is a perspective view illustrating my improved register in its open position ready to have the orders recorded on the strips therein contained. Fig. 3— is a sectional side elevation showing the mechanism with the plate in raised position, the continuous strips laid in accordion folds in the magazine and extending therefrom up over

the writing plate with the carbons between them and a portion of the cover removed. Fig. 4— is a sectional side elevation showing the device in its collapsed or closed position with the strips of slips removed therefrom. Fig. 5— is a perspective view showing the end of the magazine closing tongue. Fig. 6— shows the hinge end of the carbon sheet. Fig. 7— is a sectional end view of the writing plate.

Referring to the drawings, 1 designates the base plate of the body portion of my improved autographic register. This body portion is preferably constructed of sheet metal and provided with upwardly turned narrow side walls 2. A writing plate 3, also preferably formed of sheet metal is 70 constructed with two side walls 4—4 extending upward therefrom, these walls being also arranged to extend below the plate as at 5, see Fig. 7. The front edge of each of these upper side walls 4 is provided with 75 an opening 6 which is entered through a narrow slot 7 and is provided for the reception of the hinge ends hereinafter described. A set of standards 8 are pivoted at their upper ends at 9 to the inner side 80 of the downwardly extending flange portion 5 of this plate while the lower ends of these standards are pivoted near their forward or front edges 10 to the flange 2 of the body portion so that their rear edges 31 will 85 contact with the bottom of the body to form stops limiting the opening movement of said standards substantially at or just beyond an upright position.

A cover member 11 is provided with side 90 walls 12 which are pivoted at 13 to the side walls 2 of the body portion, and a connector member 14 is pivoted at one end 15 to the rear standard 8, said connector being slotted at 16, the outer end of the slotted 95 portion engages the pin 17 when the cover is open, whereby the last opening action of the cover moves the standards 8 upward and raises the writing plate to its operating position above the body portion, the space between the writing plate and the base of the body portion forming a magazine into which the plurality of continuous strips of paper or the like are laid with accordion-like folds. A loose plate 18 is hinged at 19 by the yoke 20 to the outer edge of the cover,

whereby this plate may be readily lifted by its outwardly bent end 21 to permit the used strips to be passed thereunder, or, if desired, to be thrown completely over back out of the way. The plate being also jointed to the yoke at the point 22 is adapted to readily accommodate itself to any thicknesses of strips which may be passed thereunder.

I preferably cover the frame of the whole device with thin leather which lends to the same an attractive and handsome appearance. A flexible flap member 23 is formed of this leather and is secured to the outer end of the cover so as to partially close this end when the cover of the register is in closed position. A loose bellows tongue 24 also formed of this leather covering, extends outward from the front end of the base of the body portion. The end of this tongue is provided with a thin metal cross bar 25, see Fig. 5, which bar extends out beyond the edges thereof and is adapted to be passed down through the opening 7 into the recesses 6 to lock and hold the free end of this tongue over the end of the writing plate to protect the strips as they are drawn from the magazine over said plate. I have also provided a simple and effective means for holding the sheets of carbon in the required position, which is that of entering the margin at one end of the sheet between the folds of the metal strip 27, which rigidly holds and binds this edge of the sheet. The ends 28 of this strip extend outward and are adapted to enter through the slot 7 into the opening 6 whereby the one edge of each carbon is held so that their free ends will lie in line with the travel of the continuous sales slips. By this construction the carbons may be readily removed and fresh ones inserted and they are always bound to hang smooth and unwrinkled over the writing plate between the strips.

My improved collapsible autographic register when in its closed position is very neat and compact and well adapted to be carried about in the pocket of the salesman, it being particularly designed for taking door step orders. The register may be supplied with any number of continuous strips, three being shown, which is the number usually employed with this device. These strips are preferably perforated, which perforations cause the strips to bend equally keeping them exactly together in their correct relative positions. The three strips are led from the magazine around the front end of the writing plate between the two carbons, illustrated by the dot dash line at 29 and 30 respectively, which are held at their front ends by means of the metal hinges 27. When the order is taken it is written down on the strip which registers also, by means of the carbon paper, on the duplicate and triplicate. The whole are then drawn by hand

and deposited under the retaining plate at 8 in the cover, which now forms a receptacle for the used portions of the strips.

After the day's orders are taken on these strips they may be all retained together and placed back into the magazine and when the orders are being filled at the store the strips are again passed between the carbons on the writing plate to receive the price marks, corrections, etc., after which the original portion is torn off to form a sales slip to accompany the order, the duplicate portion is also severed to form a slip which may be filed for bookkeeping purposes, while the triplicate portion may be retained in a continuous strip and by being bound, by suitable means, may form an audit book to be filed away for record. The last opening motion of the cover, as will be seen by the connections 14, swings and raises the writing plate above the magazine chamber, releases the folds of the strips therein contained and permits them to be readily withdrawn therefrom.

The cover, as will be seen, is retained on a slight reclining angle whereby it is adapted to form a convenient receptacle into which the used strips may be deposited. After the order has been taken it is only necessary to swing the cover back over the writing plate again. The latter part of the motion of this action swings the standards forward lowering the writing plate into position illustrated in Fig. 4 where it binds and holds the paper in the magazine.

I claim:

1. An autographic register comprising a body portion forming a magazine for memorandum strips, a writing plate connected with said body portion, a hinged cover for said body, and means operated by said cover for raising and lowering said writing plate.

2. An autographic register comprising a body portion forming a magazine for memorandum strips, a writing plate connected with said body portion, a hinged cover for said body, means operated by said cover for raising and lowering said writing plate, and means carried by said cover for retaining the writing sheets.

3. An autographic register comprising a body portion forming a magazine for memorandum strips, a writing plate movable with respect to said body portion, and means for moving said writing plate toward and from said magazine, and means for maintaining said writing plate in parallel relation with the bottom of said magazine during movement of the plate.

4. An autographic register comprising a body portion forming a magazine for memorandum strips, a writing plate movable with respect to said body portion, a cover for the magazine and writing plate, and means operated by the cover for effecting a

relative movement between the body portion and the writing plate.

5. An autographic register comprising a body portion, a cover pivotally connected thereto, a magazine in the body portion for containing memorandum strips, a writing plate movable with respect to said body portion, means operated by the cover for effecting a movement of said plate relative to said body, and means for rendering said moving means inoperative during a portion of the pivotal movement of said cover in either direction.

6. An autographic register comprising a body portion, a cover hinged thereto, a magazine in the body portion for containing memorandum strips, a writing plate movable with respect to said body portion and over which said strips are passed, means operated by said cover for raising and lowering said plate, and means in the cover for releasably engaging the strips therein.

7. An autographic register comprising a body portion, a cover hinged thereto, a magazine in the body portion for containing memorandum strips, a writing plate, standards pivotally mounted in the body portion and supporting said plate, and links connecting said cover and standards, whereby said standards are operated to move the plate when the cover is opened or closed.

8. An autographic register comprising a

body portion, a cover hinged thereto, a magazine in the body portion for containing memorandum strips, a writing plate, standards pivotally mounted in the body portion for supporting said plate, links connecting said cover and said standards, whereby said standards are operated to move the plate when the cover is opened or closed, and stops limiting the opening movement of the standards and also for retaining the cover at an angle to the plane of said plate.

9. An autographic register comprising a body portion, a cover pivotally connected thereto, a magazine in the body portion for containing memorandum strips, a writing plate, means operated by the cover for effecting a relative movement between the body portion and said plate, means for rendering said cover moving means inoperative during a portion of the pivotal movement of said cover in either direction, and a flexible member connecting the lower portion of the magazine and the writing plate to retain and guide the strips passing from the magazine to said plate.

In testimony whereof I affix my signature in presence of two witnesses.

WHITFIELD J. HAINER.
